(57) **CLAIM**

I claim the original design for a golf ball fetch toy, as shown and described.

DESCRIPTION

FIG. 1 is a front view of the invention;

FIG. 2 is a back view thereof;

FIG. 3 is a right side view thereof;

FIG. 4 is a left side view thereof;

FIG. 5 is a top plan view thereof; and,

FIG. 6 is a bottom plan view thereof.

The broken lines are for illustrative purposes only and form no part of the claimed design.
